UNITED STATES PATENT OFFICE.

NICHOLAS DIAMANT, OF JAMESTOWN, NEW YORK, ASSIGNOR TO JAMESTOWN CAR PARTS MFG. CO., INC., OF JAMESTOWN, NEW YORK, A CORPORATION OF NEW YORK.

RADIATOR.

Application filed December 3, 1923. Serial No. 678,106.

This invention relates to an improvement in radiators for cooling the engine used in automobiles, trucks, tractors and other automotive vehicles, and more particularly to a 5 radiator of the cellular type in which are provided vertical water conduits and horizontal air conduits, the air passing through the latter conduits acting to cool the water in the former conduits.

10 The primary object of this invention is to increase the efficiency of such a radiator by manipulating and directing the flow of the air and water and at the same time to increase the strength and the stiffness of 15 the radiator assembly.

A further object of this invention is to provide a radiator having a plurality of substantially vertical strips, said strips being provided with indentations or protrusions to 20 facilitate the flow of the water through the water conduits and at the same time create a turbulence in the air passing through the air conduits, whereby during the passage of 25 the air each particle thereof is brought into intimate contact with the walls of the conduits.

Other objects will appear from a consideration of the following description taken in connection with the accompanying drawing, 30 which forms a part thereof and in which

Fig. 1 is a fragmentary front illustration of a radiator embodying one form of this invention;

Fig. 2 is a fragmentary transverse section 35 of such radiator.

Fig. 3 is a plan view taken partly in section along the line 3—3 of Fig. 2;

Figs. 4 and 5 are longitudinal cross sections of wall strips employed in one embodiment of this invention;

Fig. 6 is a similar view of a separator or spacing strip;

Fig. 7 is a similar view of another form of separator or spacing strip;

Fig. 8 is a side elevation of a portion of the wall strip shown in Fig. 4;

Fig. 9 is a similar side elevation of the separator strip shown in Fig. 6.

It is well known that the rate of heat exchange is higher when the flow of the cooling medium is turbulent than when it is more or less tranquil or in a stream-line. This applies particularly in the use of water, air or similar materials as cooling mediums.

However, it is not sufficient that the flow be 55 made turbulent, but the flow of the cooling medium should be dynamically balanced, so that the energy consumed in breaking up the flow into eddies and thus causing turbulence shall be less than the gain in the rate of 60 heat exchange. For example: if the mouth of the air passage is reduced, it is possible to set up in the air passage a violent turbulence due to the well known principle of sudden expansion and this turbulence does per-

force increase the heat exchange several fold. However, the amount of power or energy required to force the air through the restricted opening becomes so great that it overbalances 65 the increase in heat exchange attained.

Furthermore, another point must be considered and that is the maintenance of a balance between the thermal and dynamic characteristics of the air passage. This is 70 particularly desirable in a radiator of the type illustrated, in which there is a peculiar temperature distribution due to the fact that the wall strips are in direct contact with the water to be cooled and their temperature is 75 higher than that of the separator or spacing strips, the temperature of which will be 80 lower than that of the wall strips since they derive their heat therefrom.

From this brief statement it will be observed 85 that it is essential to provide efficient dynamic balance between the passage of the air and the passage of the water, so as to produce eddies and turbulence without unduly interfering with the flow of either air or water, and it is also essential to obtain a thermal 90 and dynamic balance in the air passages so that the velocity distribution and the temperature distribution in the air passages shall be such that the heat exchange capacity per unit surface shall attain a maximum value.

In order to obtain these results, I have provided in the wall strips and the separator or spacing strips indentations or projections of such dimensions that they are easily embossed or stamped on the strips and are integral parts thereof. This is the preferred form and under some circumstances the dimensions of the indentations or projections on the separator or spacing strips may be such that the metal of the strips is cut or slit, 100 longitudinally, i. e., parallel to the front face of the radiator. This location of the slits is permissible because when so formed they do 105

not interfere with the passage of the heat from the wall strips to the separator strips, whereas, if the cut or slit is made transversely, it will interfere with the flow of heat from the wall strips and thus affect deleteriously the temperature distribution in the air conduits.

Referring to the drawing, the reference numeral 20 is employed to designate a radiator assembly, such assembly comprising as in the general case, an upper water tank 21, a lower water tank 22, vertical water conduits 23, connecting such tanks and horizontal air conduits 24, 25 in contact with the water conduits. The water conduits are formed by a series of thin metal wall strips 26, which also act to form one wall of the air conduits. Referring to Fig. 2, it will be noted that the water conduits 23 are formed by the wall strips 26 arranged in pairs, and that immediately contacting with the outer faces of the wall strips are separator or spacing strips 27, which constitute the other walls of the air conduits 24, 25.

25 The structure and operation of a radiator of the particular embodiment shown, when used in connection with the engine of an automobile, are old, and need not be described in greater detail. It may be briefly stated, however, that the water from the cooling system of the engine enters the tank 21 and flows through the conduits 23 into the tank 22, from which it is returned to the engine. The water flows from the tank 21 to the tank 22 in a thin film or sheet and the air passing through the air conduits 24, 25 usually under the influence of a fan, acts upon the wall strips 26, extracting heat therefrom and thereby reducing the temperature of the water.

40 These strips as illustrated in Figs. 4, 5, and 8, are of the general zig-zag type, disclosed in the patent to Ellison, Serial 1,205,874, dated November 21st, 1916, having the flattened portions 28 in contact with the separator or spacing strips 27 and the flattened portions 29 out of contact thereof. In the portions 29 are provided a horizontal series of vertical indentations 30 as shown, for example, in Fig. 4. The advantages of these indentations are two fold: first, to provide freer passages through the conduit for the water; and second, to increase the turbulence of the air in the conduits, as will be described later. The indentations are formed only at intervals and the greater part of the water follows the usual zig-zag course. This construction increases the speed with which the water passes from the tank 21 to the tank 22 and thus increases the efficiency of the radiator.

55 60 The separator or spacing strips 27 are provided with a series of projections 31 arranged in pairs and separated by flattened portions 32. These projections may be made in any desired form, such as for example, that shown in Fig. 6 in which the projections are

in the form of domes, while, in the embodiment shown in Fig. 7 the projections 31^a are in the form of truncated pyramids.

These projections are preferably arranged alternately in a horizontal plane while in a vertical plane the projections may be in the same directions as shown in Figs. 6 and 9, or in alternate directions, as shown in Fig. 7. Referring to the drawing, it will be noted that in Fig. 9 the projections 31 indicated by the numeral 33 are outward while those indicated by the numeral 34 are inward.

The side edges of the wall strips 26 and the separator or spacing strips 27 are provided with large bends 40 and small bends 41 such as are shown in the Ellison patent above mentioned, the angles of said bends being of the same magnitude, and facing in the same direction. When assembled, the large bends in the side edges of each plate are nested in the small bends of the adjacent plate and are secured thereto throughout the entire length of the small bend.

20 The separator or spacing strips 27 are provided adjacent the side edges with flattened portions 42, 43, which, as shown particularly in Fig. 1, coact with the flattened portions 28 and 29 of the wall strip 26 to constrict the mouths of the air conduits. The portions 42, 43 as shown particularly in Fig. 9 are adjacent both side edges and cause the appearance of the radiator to be the same from each side and increase the strength and stiffness of the separator strips. The portions 42, 43 with the projections 31 in the separator or spacing strips 27 and the reverse of the indentation 30 in the wall strips 26 function to produce eddies in the air passing through the air conduits 24, 25 and thus increase the turbulence thereof. The location and dimensions of these eddy producing elements are, however, such that thermal and dynamic balance in the passages is secured by controlling the velocity distribution and the temperature distribution so as to attain maximum value for the radiator.

100 While certain embodiments of this invention have been shown and described, I am not to be limited thereto since others may be made without departing from the scope and spirit 115 of the invention as set forth in the following claims.

110 It will be understood moreover, that while the improvements which constitute my invention are illustrated as applied to a radiator of the type shown in the Ellison patent above mentioned, they can be applied to cellular radiators of any type equally well, and I am not to be limited thereto other than as set forth in the claims.

120 Having thus set forth my invention what I claim as new, and for which I desire protection by Letters Patent is:

1. In a radiator, a series of zig-zag wall strips forming vertical water conduits, a

series of zig-zag separator strips forming with said wall strips horizontal air conduits, said wall strips having indentations projecting away from the water conduits and towards the air conduits and included within the corrugations of the wall strips, said indentations providing freer passages for the water in said water conduits, and increasing the turbulence of the air passing through said air conduits.

2. A radiator comprising a series of corrugated wall strips, two of said wall strips being spaced apart to form a water passage therebetween, a series of corrugated metal

division plates of single thickness so arranged between adjacent walls of said water passage that the summits of the corrugations of said division plates cooperate with said wall strips to form horizontal air conduits substantially diamond shaped and having protrusions therein projecting into said air conduits, said wall strips thereby providing freer passages for the water in said water conduits and increasing the turbulence of the air passing through said air conduits.

In testimony whereof I have affixed my signature.

NICHOLAS DIAMANT.
